UNITED STATES PATENT OFFICE.

HENRY HOWARD FREER, OF LEICESTER, ENGLAND.

CLICKING OR LIKE CUTTING-OUT KNIFE.

Application filed January 6, 1925. Serial No. 847.

To all whom it may concern:

Be it known that I, HENRY HOWARD FREER, a subject of the King of England, residing at Leicester, England, have invented 5 certain new and useful Improvements in Clicking or like Cutting-Out Knives, of which the following is a specification.

This invention relates to clicking or like cutting-out knives for cutting leather, fabric, paper or the like into various shapes by means of a press, and concerns that type of built-up clicking or cutting-out knife comprising a strip of metal having one edge 10 formed as a cutting-edge and bent to the shape required, and a backing-plate or the like to which the said metal strip is secured.

According to this invention the backing-plate is constituted by a sheet metal blank 15 with a bent edge, and the cutting-strip is secured to this edge, for example by riveting. Preferably the cutting-strip is secured to the inside of the said edge.

The edge may be constituted by a series of lugs either secured to, or integral with, the 20 backing-plate so that the edge can be bent to conform to the curvature of the cutting-strip in certain patterns.

Other features of the invention will be hereinafter described and pointed out in the 25 claims.

In the accompanying drawings:

Figure 1 is a perspective view of a clicking knife according to this invention.

Figure 2 is a plan of the backing-plate 30 prior to bending up the edge; and

Figure 3 is an enlarged sectional view of a portion of the knife.

Like reference numerals refer to like parts in the various figures.

In the specific construction shown in the drawings, the clicking knife comprises a backing-plate 4, preferably of a light metal, such as aluminum, having a bent edge 5 to which is secured, by rivets 6, the knife proper constituted by a strip of steel 7 having a cutting-edge 8.

For the backing-plate a metal blank stamped to the required shape is perforated all round at a convenient distance from the 50 edge with a number of D-shaped perforations 9 whereof the flat sides lie towards the centre of the blank and along lines which represent the outline of the shape to be cut. The metal of the blank outside these lines is then bent over to form the edge 5, and, in 55 order to negotiate the curves in the pattern,

the metal between the edge of the blank and certain perforations is cut through, as at 10, thus leaving a series of independent lugs 11. The cutter-strip 7, which may be about $1\frac{1}{2}$ 60 inch wide, is bent to shape on a mandrel and is secured to the inside of the edge 5, as shown, although, obviously, any other means of securing the strip may be employed. One or more holes 12 are provided in the backing-plate for the purpose of accommodating a plunger or the like for liberating the cut blanks of material. 65

The knife thus produced is very light and rigid and the cost of manufacture thereof is 70 considerably less than the usual type of clicking knife made in one solid piece. The above construction is given by way of example only. Obviously, instead of the perforations, the edge of the plate can be slotted 75 all round to constitute a series of lugs.

What I claim as my invention and desire to secure by Letters Patent is:

1. A cutting-out knife of the kind described comprising in combination a sheet-metal backing-plate having a rim constituted by a turned-down edge thereof, a cutting-strip and means securing said cutting strip to said rim. 80

2. A cutting-out knife of the kind described comprising in combination a sheet-metal backing-plate, and a cutting-strip bent to conform to the contour required and secured near one of its edges to said backing-plate to stand at right angles to the general 90 plane thereof with its cutting edge directed away from the said plate. 85

3. A cutting-out knife of the kind described comprising in combination a sheet-metal backing-plate, a rim on said backing-plate substantially at right angles to the general plane thereof, and a cutting-strip secured to said rim. 95

4. A cutting-out knife of the kind described comprising in combination a sheet-metal backing-plate, a rim around the edge of said backing-plate and substantially at right angles to the general plane thereof, a cutting-strip and means securing said cutting strip to said rim. 100

5. A cutting-out knife of the kind described comprising in combination a sheet-metal backing-plate having a rim around the edges thereof substantially at right angles to the general plane of the plate, and 110 a cutting-strip secured to the inside of said rim to lie parallel therewith with one of its

- edges butting against said backing-plate.
6. A cutting-out knife of the kind described comprising in combination a sheet-metal backing-plate having a rim constituted by a down-turned edge of the plate, and a cutting-strip bent to the shape required riveted to said rim, substantially as set forth.
7. A cutting-out knife of the kind described comprising in combination a sheet-metal backing-plate having a rim constituted by a plurality of lugs, secured to said backing-plate substantially at right angles to the general plane of the plate; a cutting-strip and means securing said cutting-strip to said lugs substantially as set forth.
8. A cutting-out knife of the kind described comprising in combination a sheet-metal backing-plate having a rim constituted by a plurality of lugs and a cutting-strip secured to the inside of said rim.
9. A cutting-out knife of the kind described comprising in combination a backing-plate perforated along lines which represent the contour of the knife to be formed and having its marginal portions turned down along said lines to constitute a rim; a cutting-strip and means securing said cutting-strip to said rim substantially as set forth.
10. A cutting-out knife of the kind described comprising in combination a sheet-metal backing-plate perforated along lines which represent the contour of the knife to be formed and having its marginal portions turned-down along said lines to constitute a rim, and a cutting strip secured to said rim at right angles to the general plane of the plate, substantially as set forth.
11. A cutting-out knife of the kind described comprising in combination a backing-plate having its edges slotted at intervals to constitute a plurality of lugs which are turned down at right angles to the general plane of the plate to constitute a rim; a cutting-strip and means securing said cutting-strip to said lugs, substantially as set forth.
12. A cutting-out knife of the kind described comprising in combination a shaped metal blank perforated around its edge with a plurality of substantially D-shaped holes whereof the flat sides of the holes lie along lines which represent the contour of the knife to be formed and having its marginal portions turned-down along said lines, a cutting-strip and means securing said cutting-strip to said marginal portions, substantially as set forth.
13. A cutting-out knife of the kind described comprising in combination a shaped metal blank perforated around its edge with a plurality of substantially D-shaped holes whereof the flat sides of the holes lie along lines which represent the contour of the knife to be formed and having its marginal portions turned down along said lines, a cutting-strip shaped to lie along said lines and means securing said cutting-strip to the inside of said marginal portions, substantially as set forth.
14. A cutting-out knife of the kind described comprising in combination a shaped metal blank perforated around its edge with a plurality of substantially D-shaped holes whereof the flat sides of the holes lie along lines which represent the contour of the knife to be formed having its edge slotted to constitute a plurality of lugs, said lugs being turned down at right angles to the general plane of the plate; and a cutting-strip bent to the shape required secured to said lugs, substantially as set forth.
15. In a cutting-out knife of the kind described, a sheet-metal backing-plate comprising a shaped blank perforated around its edge with a series of substantially D-shaped holes whereof the flat sides of the holes lie along lines which represent the contour of the knife to be formed, substantially as set forth.
16. A cutting-out knife of the kind described comprising in combination a backing-plate having an orifice to accommodate a plunger to release the cut blanks and having a rim substantially at right angles to the general plane of the plate, a cutting-strip and means securing said cutting-strip to the inside of said rim, substantially as set forth.

In testimony whereof I affix my signature.
HENRY HOWARD FRCER.
